UNITED STATES PATENT OFFICE

JOHN L. CALLAHAN, OF NEW YORK, N. Y., ASSIGNOR TO RADIO CORPORATION OF AMERICA, A CORPORATION OF DELAWARE

WIRELESS RECEIVING APPARATUS

Application filed March 1, 1928. Serial No. 258,168.

This invention relates to a method of and apparatus for receiving high frequency oscillations such as are used in radio transmission and in particular to a method and apparatus for receiving continuous wave oscillations.

It is well known that transmission by continuous wave is preferable in some instances to transmission by damped waves for the reason that greater distance can be covered by the use of the same amount of power at the transmitting station. The frequencies of the propagated waves in general use, however are too high to operate the diaphragm of a telephone to produce a note audible to the human ear. Means must accordingly be provided to change or alter the frequency of the incoming signals to such a value that they produce in the telephones of the receiver a note which will be audible to the human ear.

There are many known methods of altering or reducing the incoming frequency to such a value that it will operate a telephone diaphragm to set up audible note. One of the common methods of reception now in use utilizes the so-called superheterodyne principle. The superheterodyne method now in general use has several disadvantages, the main one of which is that the low frequency high power oscillator which is connected in after the long wave or intermediate frequency amplifier and generates oscillations which are combined with the oscillations in the intermediate frequency amplifier to produce a beat note at audible frequency sets up harmonics which interfere with the incoming signal oscillations. That is, the harmonics of the low frequency high power oscillator beat with the high frequency oscillator to produce an intermediate frequency similar to that produced between the signal oscillations and the high frequency oscillator.

In my novel method and apparatus for receiving signals by continuous wave oscillations, I have overcome many of the disadvantages attendant on the use of receivers known heretofore.

According to my novel method I utilize a low power oscillator and also a high frequen-

cy high power oscillator both of which are connected in between the aerial inductance and the first detector which is generally followed by a long wave amplifier, second detector and a low frequency amplifier.

55

Although for the purpose of distinguishing the oscillators I have throughout the specification designated one oscillator as the low power oscillator and the other as the high power oscillator the terms are relative and are not intended to limit the scope of the invention.

60 The low power oscillator generates oscillations at a frequency differing from the frequency of the high power oscillator by an intermediate frequency. The incoming signal oscillations beat with the high frequency high powered oscillator to produce a second beat note at a frequency which should differ from the resultant beat note obtained from the weak oscillator and strong oscillator by an audible frequency. The resultant oscillations are passed through a long wave amplifier to the second detector to obtain a resultant beat note at audible frequency which is amplified and set up in the receiver.

65 An apparent outstanding advantage of a device arranged in accordance with my invention is that the added high frequency oscillator may be so weak that it does not need shielding. This oscillator may in fact be of a strength equivalent to the strength of the incoming signal oscillations.

70 A further advantage to be gained by the utilization of my invention lies in the fact that the high frequency low power oscillator can operate at a frequency which differs from the frequency of the high power oscillator by a constant value and accordingly the oscillators may be mechanically coupled to tune as a single unit. Obviously since the antenna inductance is tuned the use of my arrangement does not increase the number of tuning points over the number used in the ordinary receiver of this type.

75 Another advantage to be gained by my invention lies in the fact that it can be adapted to broadcast receivers now in use since little or no difficulty is encountered in breaking

into such receivers to couple in the high frequency low power oscillator.

Other objects and advantages will become apparent in part from the following specification and in part from the specification when read in connection with the accompanying drawing in which:

Fig. 1 illustrates diagrammatically my novel method and arrangement for receiving continuous waves.

Fig. 1a illustrates the frequency control means for the oscillation circuits shown in Fig. 1.

In the drawing 1 is the aerial. 2 is the aerial inductance which should preferably be tuned to such a degree that only the desired signal is allowed to be set up therein. 3 is a radio frequency amplifier. 4 is the low power high frequency oscillator which generates oscillations at a frequency which differs by a constant from the frequency of the oscillations generated by the high power oscillator 5. 5 is the high power high frequency oscillator which generates oscillations to beat with the oscillations of the incoming signal and also with the oscillations of the low power high frequency oscillator. The relative positions of these two oscillators is immaterial, that is, oscillator 5 may be placed after the weak oscillator 4 as shown in the drawing or it may be placed ahead of the weak oscillator 4. 6 is the long wave amplifier which includes a first detector, an amplifier stage or stages and a second detector. The amplifier stages in this unit should consist of two circuits each tuned to a different frequency or as indicated in the drawing consist of one unit which is tuned broad enough to pass a band of frequencies, that is, oscillations at two frequencies which differ from each other by an audible frequency as indicated in the drawing. The oscillations in the intermediate frequency amplifier beat to produce a resultant or beat note at an audible frequency which by means of the second detector sets up an audible note in the low frequency amplifier 7, which will be heard in the receiver 8.

While the frequencies of the oscillators and the intermediate amplifiers used are immaterial, for purposes of illustration assume the incoming signal as being at 500 kilocycles, the weak oscillation as being tuned to 501 kilocycles, the high frequency high power oscillator being tuned at 560 kilocycles and the long wave amplifier as being tuned to 59 and 60 kilocycles. A resultant 59 kilocycle beat note is obtained in the output circuit of the first detector of the intermediate frequency amplifier 6 from the beat note of the weak oscillator and the high power oscillator. A 60 kilocycle note is obtained in the output of the first detector of the intermediate frequency amplifier from the incoming signals at 500 kilocycles and the high power oscil-

lator at 560 kilocycles. The oscillations at 59 and 60 kilocycles after being amplified in the amplifier stages of 6 are set up in the input circuit of the second detector of the long wave amplifier 6 to produce a beat note at 1,000 cycles in the output circuit thereof. This beat note is amplified in the low frequency amplifier 7, and will be audible in the telephone, or other indicating device 8.

It will be understood that this method of reception may be carried out with broadcast receivers now in use by adding the low power oscillator.

Although for purposes of illustration I have fully described the at present preferred form of my invention and the operation thereof, I do not limit myself thereby except as marked out in the following claims:

1. The method of receiving radio signals which consist in setting up oscillations at the signal frequency in a circuit, generating in said circuit a first local oscillation of an amplitude similar to the amplitude of the oscillations at signal frequency, generating in said circuit additional local oscillations of an amplitude greater than the amplitude of said first named oscillations, and utilizing the components of said oscillations to operate an indicating device.

2. A radio receiving system comprising an oscillation circuit responsive to signal frequencies, a pair of high frequency oscillation generators including oscillation circuits associated with said first named circuit, one of said generators being of low power relative to the power of the other of said generators, means for tuning one of said generators to a frequency differing from said signal frequency by an intermediate frequency, means for tuning the other of said generators to a frequency differing from the frequency of said first named generator by a constant intermediate frequency, and a single control for both of said tuning means.
